LEHR DRIVE FOR SHEET GLASS MACHINES

William Owen, Pittsburgh, Pa., assignor to Pittsburgh Plate Glass Company, Allegheny County, Pa., a corporation of Pennsylvania

Application September 29, 1937, Serial No. 166,267

5 Claims. (Cl. 49—17)

The invention relates to a lehr drive for sheet glass machines, such as those employed in the Fourcault and Slingluff processes, involving the use of a series of pairs of rolls in a vertical lehr casing which grip the glass sheet between the members of each pair and provide the traction necessary for drawing the sheet continuously from a bath of molten glass in a forehearth. In accordance with the present practice, the 5 rolls on one side of the sheet are mounted in fixed bearings, while the rolls on the other side are carried in movable bearings pressed inward by weighted bell crank levels, thus providing yielding pressure between the members of each 10 pair and permitting the drawing of glass sheets of different thicknesses.

The main objects of the present invention are the provision of improved and simplified means for supporting and driving the rolls wherein, 20 (1) the pressure between the rolls of each pair is automatically controlled by the traction which the rolls are applying to the sheet being drawn, so that no weights or springs are required with the attendant adjustment heretofore necessitated, (2) the drive is smooth and uniform and no working bearings exposed to the direct heat of the lehr are required, permitting bearings of the greaseless type to be employed throughout, (3) the parts are easily assembled and disassembled permitting the ready replacement of the rolls when wasting away of the relatively soft roll surfaces calls for such replacements, (4) the rolls are driven from both ends thus avoiding roll twist, (5) the rolls throughout the lehr may be 25 separated automatically by merely reversing the drive, when it is desired to pass a bait downward through the lehr for initiating the draw, and (6) the weight and cost of the equipment is materially decreased, as compared with structures heretofore proposed. Certain embodiments of the invention are illustrated in the accompanying drawings, wherein:

Figure 1 is a partial end elevation of the apparatus. Fig. 2 is a partial side elevation and 45 partial section. Fig. 3 is a section at two elevations on the line III—III of Fig. 1. Fig. 4 is an enlarged partial end elevation with the chain sprockets removed. Fig. 5 is a section on the line V—V of Fig. 4. And Fig. 6 is a detail section illustrating a modification.

The lehr casing which is mounted over the bath of glass (not shown) comprises the side walls 7, 7 and the end walls 8, 8, the latter serving as the support for the rolls and their driving mechanism. The glass sheet 9 is drawn up 55

continuously through the lehr casing and cut off in sections in the usual manner, and the drawing is accomplished by the series of pairs of rolls 10 carried by the shafts 11, which are preferably hollow to permit air or water cooling, the 5 rolls being preferably of the usual asbestos composition. Each roll shaft has keyed to each end a spur gear 12 and beneath each pair of spur gears is a pair of intermeshing spur gears 13 which engage the gears 12 and take the weight 10 of the rolls. The gears 13 are mounted upon pins 14 welded or otherwise secured to bars 14a (Figs. 4 and 5) which are bolted to the end walls of the casing. Greaseless bearings for the gears 13 are provided in the form of bushings 16 and 15 each gear 13 has secured to its outer end the sprocket 17. The sprockets at one end of the casing are engaged and driven by the chain 18 (Fig. 1) while those on the other end are driven by a similar chain 19 (Fig. 2). The chains pass 20 around sprockets 20 at their upper ends keyed to the countershaft 21 and this countershaft is driven from the motor 22 through the intermediary of the chain 23 which passes around a sprocket on the shaft of the motor reducer 24 25 and a sprocket 25 which is also keyed to the shaft 21. Means are thus provided for driving the rolls from both ends so that any roll twist, such as occurs when rolls are driven from one end is avoided. This is not an essential, however, as 30 it is possible to drive from one end of the rolls only in accordance with the usual practice.

The gears 12 which are keyed to the roll shafts 11 are preferably flanged, as indicated in Fig. 5, so that they are kept in proper alignment with 35 the gears 13 and only a slight amount of endwise movement of the rolls is permitted. The shafts 11 are provided at each end thereof with a greaseless metallic bushing or bearing 26 (Fig. 5) in which the shaft has a loose running fit. These bushings are preferably in two parts secured together by means of the bolts 27 and 40 are provided with flanges to prevent their endwise movement relative to the casing. They are not mounted directly in the casing walls 8, but are carried by removable plates 28 secured to the casing wall by means of bolts 29. These plates 28 are of such size that when they are detached, the rolls may be removed endwise through the space provided thus permitting ready 45 replacement. The bushings 26 are free to move freely toward and from the line of draw due to the fact that they are mounted in the oblong slots 30, 30, as indicated in Fig. 4. The drive of the intermeshing gears 13 from the chains 18 50 55

and 19 is, as indicated by the arrows in Fig. 4, which gives the drawing rolls 10 a movement of rotation, also as indicated by the arrows, thus providing an upward lift upon the glass sheet 9. It will be noted that the axes of rotation of the gears 13 are spaced apart a greater distance than the axes of rotation of the rolls. The drive of the rolls from the gears 13 thus tends to force the rolls toward each other. The grip of the rolls upon the glass sheet is, therefore, regulated automatically, the pressure upon the sheet increasing with the resistance to the draw, and as a result, no other means are required for forcing the rolls toward each other, such as weights and springs which have heretofore been required in connection with drawing rolls as used in the Fourcault and Slingluff processes. When it is desired to separate the drawing rolls to permit the passage of a bait downward therebetween to initiate the drawing operation all that is necessary is to reverse the direction of movement of the chains 18 and 19. This will cause the gears 12 to roll outward upon the supporting gears 13, such outward movement being limited by the ends of the slots 30, 30.

In some cases, it is desirable to separate the pairs of rolls successively during the upward movement of the sheet in order to avoid breakage due to stones in the glass and in order to provide for this condition, cam means are provided for each pair of rolls which are manually operated. One of these cams is shown in Figs. 4 and 5. It comprises the plate 31 pivoted on the pin 32 and provided with a notched handle 33 passing through a locking bar 34. The plate 31 engages both bushings 26 at the end of the two shafts 11, and when the handle is moved to the left (Fig. 4), the rolls are separated to any desired degree and held in such position by the handle 33. These cams are required at only one end of the rolls. Any wear upon the bushings 26 is very slight since the weight of the rolls is taken by the gears 13 which engage the gears 12 on the ends of the roll shafts. It is, therefore, feasible to use greaseless bearings which are not exposed to the heat and which require no attention.

If desired, the work of supporting the rolls may be removed from the interengaging teeth of the gears 12 and 13 by an expedient, such as indicated in Fig. 6, wherein the gear 12 is provided with a flange 35 which rests upon a flange 36 integral with the gear 13. The peripheral diameter of these flanges corresponds to the pitch diameter of the two gears so that the gears are left in normal driving engagement, but at the same time the load is removed therefrom. In this case, an inner flange is provided upon the gear 12 in the form of a plate 37 which is welded to the inner face of the gear. In order to avoid any backlash in the drive by the chains 18 and 19, these chains pass at their lower ends around sprockets 38, whose journals are adjustable downward by suitable take-up mechanism, such as the bolts 39 in the frame 40, this being an expedient well known in the art and requiring no specific description. The sprockets 38 are carried by the same cross shaft 41 (Fig. 2) mounted as indicated in Fig. 2. When it is desired to fix the position of the rolls on one side of the line of draw, this may be accomplished by using circular perforations for the bushings 26 instead of the oblong slots 30, or by putting filler members in the slots to hold the bushings against movement away from the line

of draw. Such a construction, with only the rolls on one side of the line of draw movable, will operate satisfactorily. In such case, the shape of the cams 31 are modified so that they will act only on the bushings of the movable rolls. 5

The advantages incident to the structure have been stated heretofore and will be readily apparent to those skilled in the art from a consideration of the foregoing specification in connection with the drawings. 10

What I claim is:

1. In combination in a vertical lehr for drawing and annealing a glass sheet, a casing, a pair of opposing horizontal rolls therein adapted to grip the glass sheet therebetween one of which is mounted for free movement toward and from the other roll, a spur gear secured to each end of each roll, a pair of intermeshing spur gears mounted in fixed bearings at each end of the pair of rolls on axes parallel to the axes of the 20 rolls and therebeneath in such position that they engage the spur gears on the ends of the rolls, lying thereabove and take the weight of the rolls, and means for driving one pair of said intermeshing gears, the axes of rotation of the intermeshing gears being spaced apart on opposite 25 sides of the line of draw of the sheet a distance greater than the distance separating the axes of rotation of the rolls, said gears all being located on the exterior of the casing. 30

2. In combination in a vertical lehr for drawing and annealing a glass sheet, a casing, a pair of opposing horizontal rolls therein adapted to grip the glass sheet therebetween, one of which is mounted for free movement toward and from 35 the other roll, a spur gear secured to each end of each roll, a pair of intermeshing spur gears mounted in fixed bearings at each end of the pair of rolls on axes parallel to the axes of the rolls and therebeneath in such position that they engage the spur gears on the ends of the rolls, lying thereabove and take the weight of the rolls, and means for driving both pairs of said intermeshing gears, the axes of rotation of the intermeshing gears being spaced apart on opposite 45 sides of the line of draw of the sheet a distance greater than the distance separating the axes of rotation of the rolls, said gears all being located on the exterior of the casing.

3. In combination in a vertical lehr for drawing and annealing a glass sheet, a casing having a pair of downwardly converging guides formed in opposed sides thereof, a pair of opposing horizontal rolls movable freely toward and away from each other in said guides and adapted to grip the glass sheet therebetween, a spur gear secured to each end of each roll, a pair of intermeshing spur gears mounted in fixed bearings at each end of the pair of rolls on axes parallel to the axes of the rolls and therebeneath in such 55 position that they engage the spur gears on the ends of the rolls lying thereabove and take the weight of the rolls, and means for driving one pair of said intermeshing gears, the axes of rotation of the intermeshing gears being spaced apart on opposite sides of the line of draw of the sheet a distance greater than the distance separating the axes of rotation of the rolls, said gears all being located on the exterior of the casing. 60

4. In combination in a vertical lehr for drawing and annealing a glass sheet, a casing, a pair of opposing horizontal rolls therein adapted to grip the glass sheet therebetween, one of which is mounted for free movement toward and from 65

- the other roll, a spur gear secured to each end of each roll, a pair of intermeshing spur gears mounted in fixed bearings at each end of the pair of rolls on axes parallel to the axes of the rolls and therebeneath in such position that they engage the spur gears on the ends of the rolls lying thereabove, cam means pivoted on the casing for moving one end of the movable roll away from the other roll, and means for driving one pair of said intermeshing gears, the axes of rotation of the intermeshing gears being spaced apart on opposite sides of the line of draw of the sheet a distance greater than the distance separating the axes of rotation of the rolls.
5. In combination in a vertical lehr for drawing and annealing a glass sheet, a casing, a pair of opposing horizontal rolls therein adapted to grip the glass sheet therebetween, a bushing at each end of one roll in which such roll is journalled mounted for sliding movement in the casing toward and from the other roll, a spur gear secured to each end of each roll, a pair of intermeshing spur gears mounted in fixed bearings at each end of the pair of rolls on axes parallel to the axes of the rolls and therebeneath in such position that they engage the spur gears on the ends of the rolls lying thereabove and take the weight of the rolls, and means for driving one pair of said intermeshing gears, the axes of rotation of the intermeshing gears being spaced apart on opposite sides of the line of draw of the sheet a distance greater than the distance separating the axes of rotation of the rolls, said gears all being located on the exterior of the casing.
10. 5. In combination in a vertical lehr for drawing and annealing a glass sheet, a casing, a pair of opposing horizontal rolls therein adapted to grip the glass sheet therebetween, a bushing at
15. 5. In combination in a vertical lehr for drawing and annealing a glass sheet, a casing, a pair of opposing horizontal rolls therein adapted to grip the glass sheet therebetween, a bushing at

WILLIAM OWEN.
